UNITED STATES PATENT OFFICE.

CLEMENT L. FLYNN, OF BELLINGHAM, WASHINGTON, ASSIGNOR TO WELLES THOMPSON COMPANY, OF MINNEAPOLIS, MINNESOTA, A CORPORATION OF MINNESOTA.

SILO.

1,254,131.

Specification of Letters Patent. Patented Jan. 22, 1918.

Application filed May 4, 1914. Serial No. 836,162.

To all whom it may concern:

Be it known that I, CLEMENT L. FLYNN, a citizen of the United States, residing at Bellingham, in the county of Whatcom and

5 State of Washington, have invented certain new and useful Improvements in Silos, of which the following is a specification.

This invention relates to silos or tanks for the storage of stock feed. The object of my 10 improvements is to afford a more rigid and inexpensive structure of this character which may be erected without the employment of skilled labor, and in which ensilage may be kept in good condition for a long 15 time.

The invention consists in the novel construction, adaptation and combination of devices, as will be hereinafter described and claimed.

20 In the accompanying drawings, Figure 1 is a fragmentary front elevational view of a silo embodying the present invention. Fig. 2 is a vertical sectional view through 2—2 of Fig. 1. Fig. 3 is a detail horizontal sectional view of the silo wall. Fig. 4 is a horizontal section through 4—4 of Fig. 2, showing a door and the jambs therefor and indicating by broken lines the manner of introducing or removing the same from the 30 door-opening.

The wall of the silo is composed of a plurality of posts 10 which are spaced to conform to the lengths of horizontal panel boards 11 and furnish the requisite door- 35 openings, such as 12. Said posts are provided in proximity of their inner faces 13 at opposite sides with arcuate shaped grooves 14 to receive the correspondingly shaped extremities of the panel-boards.

40 By the provision of such joints between the posts and the panel-boards, the latter may be disposed in various angular relations, as indicated by full and broken lines (A) in Fig. 3, according to the diameter of 45 the silo. In proximity to their outer faces said posts are preferably provided with rabbets 15 to receive the ends of horizontally disposed cover-boards 16. Said cover-boards are nailed or otherwise secured to 50 the posts and provide, with the panel-boards, air spaces or chambers between the posts.

The posts are connected in pairs by coupling rods 17 which extend through said 55 spaces and holes provided in the posts. Said

rods are screw-threaded for engaging nuts 18 and 19 at opposite sides of a post for securing the latter in adjusted positions.

The rods 17, moreover, are arranged in groups about the entire wall and serve with 60 the posts as the frame thereof. Such wall-frame is supported upon a foundation or base 20 of concrete, or other suitable material, and to which the frame is connected by anchor devices. Said anchor-devices (see 65 Figs. 1 and 2) each consist of an eye-bolt 21 having its lower portion embedded in the base 20 and, to prevent its being withdrawn therefrom, is desirably formed with a rectangular bend 21¹. Connected with 70 the eye of said bolt is a link 22 having at its upper end an eye to accommodate a coupling rod 17 and is held in juxtaposition with a post by a nut 18. To regulate the height of the link with respect to a coupling 75 rod, pockets such as indicated by broken lines B, Fig. 2, may advantageously be provided in the base 20 to receive an eye-bolt and, after setting up the frame, the pockets are successively filled with cement or con- 80 crete to unite the eye-bolts with the base.

By means of the links 22, the various posts may be moved to an extent toward or away from the center of the silo by manipulating the nuts 18 and 19 as may be required 85 to compensate for the swelling or shrinkage of the panel-boards, etc., to maintain the wall in an air-tight condition.

Above and below the referred to door- 90 openings, the headers or sills may be afforded by boards 11¹ similar to the afore-described panel-boards except that instead of being made convex and concave at their meeting edges, in this instance they are beveled, as at 24, to allow the doors to be 95 introduced into their openings from the inside of the silo and furnish seats for the door edges.

A door is comprised of two sections C and D each formed of a plurality of horizontally 100 arranged boards 25 (Fig. 2) which are matched at their upper and lower edges and are connected by vertically arranged cleat elements 26 fastened to the outer faces of the boards 25.

The outer ends 25¹ of the door sections are 105 made convex to fit the grooves 14 of the posts at each side of a door-opening and the joint between the door sections is obtained by employing convex and concave meeting 110

ends 27 and 28, respectively, of sections D and C for articulating the latter endwise.

Pairs of hinge members 29, rigidly secured to said door sections near the upper and lower ends of the same, are provided with elongated slots 30 (Fig. 4) for pivotally and slidably connecting them to the respective hinge pins 31. The hinge slots 30 are arranged to have the pins encounter the ends 30¹ of the slots when the door sections occupy the full-line positions in the view and prevent the door being collapsed outwardly through any pressure which may be applied against the same.

15 The pins 31 of the hinges of a door are formed integral with and constitute the terminals of a bail whose intermediate portion 32 is offset or stands out from the door to be engaged by the arm of a lever fulcrumed 20 against a post, as indicated by broken lines 33 in Fig. 4, being used to pry a door into the opening therefor in the silo.

Ordinarily, however, a door may be extended for engagement by an outward pull 25 by the operator upon the bail. To remove a door it is pushed inwardly by pressure exerted at or near the joint between the sections thereof, whereupon the door collapses as indicated by broken lines (Fig. 4) and the outside edges 25¹ are withdrawn from the grooves in the posts or jambs.

The aforesaid door comprised of toggle-like elements will obviously serve to wedge itself in a door-opening and be held therein 35 without the offices of any supplementary locking devices.

Copies of this patent may be obtained for five cents each, by addressing the "Commissioner of Patents.

Washington, D. C."

Witnesses:

M. J. McGARRY,
JOHN McMAHEN.

Signed at Bellingham, Wash., this 24th day of April, 1914.

CLEMENT L. FLYNN.

The bail, which constitutes a part of the door-hinges, serves as a handle whereby the door is conveniently held when introducing or removing it, as well as for applying force 40 at the knuckle when locking the door.

Having described my invention, what I claim, is—

1. The combination with a foundation for a silo, or the like structure, of circumferentially spaced upright posts resting loosely and shiftable on said foundation radially thereof, panels fitting the spaces between said posts and resting loosely over said foundation, and post anchoring devices positively anchoring said post to said foundation, against vertical movements but with freedom for radial movements.

2. The combination with a foundation for a silo, or like structure, of upright circumferentially spaced posts shiftable at their lower ends on said foundation radially thereof, panels fitting the spaces between said posts, horizontal rods adjustably connecting said posts, and post anchoring devices comprising link anchors embedded in said foundation, and links pivoted to said anchors and to the lower portions of said posts and holding the said post positively anchored to said foundation against vertical movements but free for radial movement.
